UNITED STATES PATENT OFFICE

101,030

DESIGN FOR A COMBINED ROTARY VALVE AND OPERATING MEANS

Victor E. Flodin, Oak Park, Ill., assignor to Crane
Co., Chicago, Ill., a corporation of Illinois

Application June 12, 1936, Serial No. 63,254

Term of patent 14 years

To all whom it may concern:

Be it known that I, Victor E. Flodin, a citizen of the United States, residing at Oak Park, in the county of Cook and State of Illinois, whose post-office address is 1037 North Kenilworth Avenue, Oak Park, Illinois, have invented a new, original, and ornamental Design for a Combined Rotary Valve and Operating Means, of which the following is a specification, reference being had to the accompanying drawing, forming part thereof.

The figure is a perspective view of a combined rotary valve and operating means, showing my new design, the dominant feature of which is the crown-shaped enclosure supported by the valve bonnet. The side not shown is identical with the side shown.

I claim:

The ornamental design for a combined rotary valve and operating means, substantially as shown and described.

VICTOR E. FLODIN.
